UNITED STATES PATENT OFFICE.

JOHN T. COWLES, OF CHICAGO, ILLINOIS.

BASEMENT-STAIRWAY.

No. 920,274.

Specification of Letters Patent.

Patented May 4, 1909.

Application filed July 22, 1904. Serial No. 217,749.

To all whom it may concern:

Be it known that I, JOHN T. COWLES, a citizen of the United States, residing at Chicago, in the county of Cook and State of Illinois, have invented a new and useful Basement-Stairway, of which the following is a specification.

This invention relates to basement-stairways.

10 The object of the invention is to provide a construction of basement stairway which is simple and efficient, and wherein the stairway or ladder is pivotally mounted so as to be swung up against the roof of the basement, sub-basement or other locality when not required for use, and retained in such position.

A further object of the invention is to provide a stairway of the class referred to which 20 is pivotally mounted and counterbalanced so as to be swung upwardly against the roof and out of the way when not required for use, and retained in such position by detachable holding devices, whereby by releasing such 25 devices the stairway or ladder may be lowered into position for use.

A further object of the invention is to provide a swinging stairway or ladder for use in basements, sub-basements or similar situations, with connections between the same and a pivoted section or portion of the sidewalk or roof, whereby when the ladder is swung 30 into position for use the movable section or portion of the sidewalk or roof is automatically raised to permit access through the opening thereby produced to the stairway or ladder.

A further object of the invention is to provide a swinging or movable ladder or stairway of the character referred to and a hand-rail therefor which is automatically movable 40 by the movements of the ladder or stairway into and out of position for use.

A further object of the invention is to provide an automatic stop or lock device for 45 maintaining a swinging or movable section of stairway or ladder in position for use.

A further object of the invention is to provide a ladder or stairway of the character referred to in such relation as to afford access 50 to or egress from a building in case of fire or other accident.

Other objects of the invention will appear more fully hereinafter.

The invention consists substantially in the 55 construction, combination, location and arrangement of parts, all as will be more fully

hereinafter set forth, as shown in the accompanying drawings, and finally pointed out in the appended claims.

Referring to the accompanying drawings, 60 and to the various views and reference signs appearing thereon, Figure 1 is a view in central longitudinal section of a pivoted swinging or movable stairway, showing the application thereof to the roof or under surface of 65 a sidewalk setting, the position of the parts when the ladder or stairway is folded or swung into position out of use being shown in full lines, and the position of the parts when the ladder or stairway is swung or 70 moved into position for use being indicated in dotted lines. Fig. 2 is a view in transverse section on the line 2—2, Fig. 1, looking in the direction of the arrows. Fig. 3 is a similar view, on the line 3—3, Fig. 1, looking in the 75 direction of the arrows. Fig. 4 is a detached detail view, parts broken off, showing a swinging arm for detachably supporting the ladder or stairway when the latter is swung into position out of use. Fig. 5 is a view in 80 section on the line 5—5, Fig. 4, looking in the direction of the arrows. Fig. 6 is a broken detail view in transverse section of a tread of the stair or ladder. Fig. 7 is a detail elevation of a hand rail. 85

The same part is designated by the same reference sign wherever it occurs throughout the several views.

In accordance with the principles of my invention, I propose to provide a swinging or movable stairway or ladder for use in basements, sub-basements or the like, or underneath sidewalks, for the purpose of gaining access to, or permitting egress from, a building through an opening in the sidewalk or 90 the roof of the basement or sub-basement in which the device is to be located, and I propose to pivotally mount the ladder or stairway at a convenient point intermediate the ends thereof, whereby such ladder or stairway is partially, at least, or to any desired extent, balanced or counterbalanced by its 95 own weight. I propose to provide the roof of the basement or sub-basement or the like, or the sidewalk, as the case may be, with a door or movable section, and to provide suitable connections between such door or section and the ladder or stairway, whereby when the latter is swung into position for use the former will be raised to permit ingress to or egress from the basement, sub-basement or other locality in which the appara- 100 105 110

tus is placed, through the roof or sidewalk, and in order to facilitate such ingress or egress I propose to employ a hand-rail section and provide suitable connections therefor, whereby when the ladder or stairway is swung or moved into position for use the hand or guard rail section is also moved into position to perform the function of a hand or guard rail, and I propose to provide such connections between the ladder or stairway and the movable section of guard or hand rail and also the movable section of sidewalk door as will enable these parts to be returned or restored to initial position, the former out 15 of the way and the latter in closing relation with respect to the opening in the roof of the basement, sub-basement or the like or in the sidewalk whenever the ladder or stairway is swung or moved into position out of the way. 20 It is important to provide means for supporting the ladder or stairway in position out of the way when not required for use, and I therefore propose to so arrange the parts as that the ladder or stairway may be swung 25 upwardly, if desired, against or in proximity to the roof of the basement or under the surface of the sidewalk, and I provide readily detachable retaining devices for the ladder when occupying this position. Where I employ a ladder or stairway which is pivotally supported at a point intermediate the ends thereof to secure the balancing or counterbalancing effect it is desirable to provide means whereby when the ladder or stairway 30 is moved into position for use it will be automatically locked and retained in such position so as to avoid the possibility of the weight of a person, when imposed on the ladder or stairway, operating to displace the 35 same about the hinge or axis upon which it is pivoted. In accordance with my invention, therefore, I propose to employ detachable locking devices for locking automatically the stairway or ladder when swung or moved into position for use. 40

Many specifically different constructions and arrangements of apparatus for accomplishing the objects and purposes above outlined may be devised. While, therefore, I 45 have shown and will now describe a construction embodying the principles set forth, I desire it to be understood that my invention is not to be limited or restricted to the details or specific construction and arrangement of such devices.

In the drawings, reference sign A designates a sidewalk setting, or the roof of a basement, sub-basement or the like. B designates hangers, suitably supported or secured 60 to the under surface thereof.

C is a rod supported by the hangers B, and serving as a hinging axis for a ladder or stairway section D.

In practice I propose to hinge or pivot the 65 stairway or ladder section D upon rod C at a

convenient point intermediate the ends of the ladder or stairway, thereby securing a more or less counterbalancing effect, depending upon the position of the hinge or pivot rod with respect to the length of the ladder 70 or stairway section. The ladder or stairway may be of any suitable or convenient construction, including risers E, of any desired construction, and I propose to provide the ladder or stairway with a railing, indicated 75 generally by reference sign F, to serve the purpose of a hand rail or guard.

By hinging or pivoting the ladder or stairway section as above described I am enabled to rock or swing the same upwardly against 80 the roof or under side of the sidewalk when the ladder or stairway is not required for use, whereby it is out of the way and occupies comparatively small space.

In order to support and retain the ladder 85 when swung upwardly and out of the way and against or underneath the roof or sidewalk, I provide the ladder with a supporting pin or stud G, (see Figs. 1, 4 and 5) with which engages a swinging arm H, having a 90 hooked end J, arranged to engage underneath the pin or stud G. The arm H is pivotally hung or suspended from the roof or ceiling, as clearly shown in Fig. 1, the hooked end J being provided at the lower extremity 95 thereof. Any convenient means for detaching the hook supporting arm J from supporting or engaging relation with respect to the stud or pin G may be provided, whereby the ladder or stairway section may be detached 100 from its support or retaining device when it is desired to lower the same for use. I have shown a simple arrangement for accomplishing this object, comprising a hand cord K, attached at one end to the ladder or stairway 105 section at a point above the hooked end J of supporting arm H, and led downwardly from its point of connection to the ladder underneath the pin or stud G, and around the extremity of the hooked arm J, and depending vertically therefrom. From this construction it will be seen that by pulling upon the hand rope or cord K the retaining arm H will be swung out of engaging or supporting relation with respect to stud G, thereby releasing 115 the ladder section or stairway and permitting the same to rock or swing downwardly into position for use. If necessary, in case of a sufficiently balanced or counterbalanced stairway, a connection K will afford means 120 not only for detaching the supporting arm H, but it will also serve as a means for pulling down the free end of the ladder or stairway section. If desired, and in order to reduce friction and to facilitate the detachment of 125 the arm H, the free end of the hooked portion J thereof may be provided with a roller L, over which the hand cord or rope K is passed.

When the ladder is lowered into position for use it is desirable that the opening in the 130

roof or ceiling of the basement or the like or the sidewalk be uncovered. To this end I provide such roof or sidewalk with a hinged or movable section or door M, and in order 5 that such door may be opened or closed automatically by the swinging movements of the stairway or ladder section, I pivotally connect rods or bars N at one end to the under surface of the door M, and at a convenient point therein, and I connect the other 10 end of such arm to the ladder or stairway section, the points of connection of said arm to the door and ladder being respectively on opposite sides of the hinging axis and pivot 15 of the ladder or stairway section and in such relation that when the ladder or stairway section is rocked or swung upwardly against the roof or ceiling as indicated in full lines in Fig. 1, the door M will be automatically and 20 simultaneously closed, and when the ladder or stairway section is swung into position for use the door M will be opened, as indicated in dotted lines in Fig. 1.

In order to facilitate the passage of persons up and down the ladder or stairway section when the latter is in position for use 25 I propose to employ a hand rail section adapted to be moved automatically by the movements of the ladder or stairway into 30 and out of position to form a hand or guard rail, according as the ladder or stairway section is in position for use or is folded or 35 swung upwardly against the roof or ceiling. Many specifically different constructions of automatically movable hand rail sections 40 may be employed for this purpose. I have shown a simple arrangement, comprising arc-shaped arms O P, connected together, and one of said arms pivotally connected to 45 the stairway or ladder section. An arm Q is pivotally connected at one end to the roof or ceiling, preferably by means of a slotted connection and the other end is connected to the arm P, which latter may form a continuation of the arm Q, if desired. By this 50 construction it will be seen that when the ladder or stairway section is rocked or swung upwardly against the roof or ceiling the arm Q will adjust itself by means of the slotted connection with the roof so that the hand rail section O P will be retracted into the 55 position shown in full lines in Fig. 1, and when the ladder or stairway section is swung downwardly into position for use the hand rail sections O P are raised upwardly through the opening in the roof ceiling or sidewalk into position to perform the function of a hand or guard rail, as indicated in dotted lines in Fig. 1.

60 In order to lock the ladder or stairway in the position occupied thereby when lowered for use so as to avoid the danger of the weight of a person imposed thereon rocking, overbalancing or swinging such ladder or

stairway section I provide depending spring 65 arms R on opposite sides of the ladder or stairway, such arms being secured to the roof or ceiling and depending therefrom, and I provide such spring arms with shoulders S. On adjacent sides of the stairway or ladder 70 I provide coöperating lugs or projections T, which as the ladder is rocked or swung into position for use snap over the shoulders or lugs S of spring arms R, thereby constituting a locking mechanism for locking and 75 retaining the ladder in position.

When the use of the ladder has been completed and it is desired to rock or swing the same back to its initial position against the under side of the roof or ceiling the spring 80 arms R may be separated in any convenient manner to carry the shoulders S thereon out of engaging relation with respect to the engaging shoulders T. This may be accomplished in many specifically different ways. 85 I have shown a simple arrangement, to which, however, my invention is not to be limited or restricted, wherein a lever A' is pivotally connected to a hanger B', depending from the ladder, and rods C' are connected on opposite 90 sides of the point of pivotal connection of lever A' to hanger B' and are arranged with the free ends thereof to project into proximity to the free ends of spring arms R. By 95 rocking lever A' the rods C' are projected longitudinally to engage the free ends of spring arms R, thereby moving the same out of engaging relation with respect to the shoulders T. Lever A' may be rocked in any convenient manner, as, for instance, by means of a 100 hand cord or rope D', suitably connected to the lever A'. If desired, a spring E' may be connected between hanger B' and lever A' to normally maintain the latter in position to withdraw the free ends of rods C' from 105 engaging relation respectively with the spring arms R.

By employing a ladder or stairway section embodying the construction above described underneath the ordinary glass setting of sidewalks of buildings, it will be apparent that I provide means for gaining access to or egress 110 from a building in time of fire or accident through the basement, and which apparatus may be reached either from the basement or 115 in case of emergency from the sidewalk by breaking the glass setting of the sidewalk and releasing the retaining devices which retain the ladder against the ceiling of the roof of the basement, and this I regard as a most 120 important characteristic of my invention.

As above indicated, many variations and changes in the details of construction and arrangement would readily occur to persons skilled in the art and still fall within the spirit and scope of my invention. I do not desire, therefore, to be limited or restricted 125 to the exact details shown and described; but

Haying now set forth the object and nature of my invention and a construction embodying the principles thereof, what I claim as new and useful and of my own invention, and desire to secure by Letters Patent, is:

1. The combination of a sidewalk or basement roof, having a door-way or opening, a step section pivotally suspended from the under side of said sidewalk or roof, a pivoted 10 guard-rail, and connections between the step section and guard-rail, said guard-rail being adapted to be moyed about its pivot and passed through the opening when the step section is moved into position for use.
- 15 2. The combination of a sidewalk or basement roof, having a door-way or opening, a pivotally suspended step section, a guard-rail mounted upon a movable pivot point, and connections between the step section and 20 rail for moving the latter about its pivot,

whereby the said rail will be passed through the opening when the step section is moved.

3. The combination with a sidewalk or basement roof, of brackets suspended from the ceiling thereof, a ladder or stairway section hinged or pivoted to said brackets or 25 hangers and provided with lugs or shoulders, spring arms arranged to be engaged by said lugs or shoulders to lock said ladder in position for use, and means for detaching said spring arms from engaging relation with respect to said shoulders to release the ladder or stairway section.

In witness whereof, I have hereunto set my hand this 20th day of July 1904, in the presence of the subscribing witnesses.

JOHN T. COWLES.
